UNITED STATES PATENT OFFICE.

CHARLES A. DEMPSEY, OF WEST CHICAGO, ILLINOIS, ASSIGNOR OF ONE-HALF TO JOHN F. FOWLER, OF WEST CHICAGO, ILLINOIS.

DRILL.

1,121,171.

Specification of Letters Patent. Patented Dec. 15, 1914.

Application filed January 20, 1914. Serial No. 818,283.

To all whom it may concern:

Be it known that I, CHARLES A. DEMPSEY, a citizen of the United States, residing at West Chicago, in the county of DuPage and 5 State of Illinois, have invented a new and useful Drill, of which the following is a specification.

The invention relates to improvements in drills.

10 The object of the present invention is to improve the construction of well drills, and to provide a simple, efficient and inexpensive safety device adapted to cover and protect an entire string of tools, and capable in 15 event of breakage of any portion of the string above the point to which its lower end is applied of enabling the tools to be jarred up and removed from the well.

A further object of the invention is to 20 provide a safety device of this character adapted to strengthen a string of tools, maintain them in a straight line and enable a straight hole to be bored and at the same time prevent foreign matter, such as rock, 25 sand, sediment, etc., from getting between the links of the jars and locking or interfering with the operation thereof.

With these and other objects in view, the 30 invention consists in the construction and novel combination of parts hereinafter fully described, illustrated in the accompanying drawing, and pointed out in the claims here- 35 to appended; it being understood that various changes in the form, proportion, size and minor details of construction, within the scope of the claims, may be resorted to without departing from the spirit or sacrificing any of the advantages of the invention.

40 In the drawing:—Figure 1 is an elevation of a string of tools equipped with a safety device, constructed in accordance with this invention, the safety device being in section. Fig. 2 is an enlarged sectional 45 view of the safety device. Fig. 3 is an enlarged detail view of the upper portion of the rope socket. Fig. 4 is a similar view of a portion of the bit.

Like numerals of reference designate cor- 50 responding parts in all the figures of the drawing.

In the accompanying drawing in which is illustrated the preferred embodiment of the invention, the safety device comprises in

its construction a tubular casing or safety sleeve 1 connected at its lower end by a coupling section or member 2 to the bit 3 of a string of tools and having a slidable connection at its upper end with the rope socket 4 of the said string of tools. The 50 string of tools, which is of the ordinary construction, comprises the bit 3, the rope socket 4, a stem 5 and jars 6 composed of links and operable in the usual manner. The bit 3 is provided at its upper portion 55 with a threaded boss 7 and the coupling sleeve or member 2, which is preferably cylindrical, as shown, is provided at its lower end with interior screw threads 8 to engage the threaded boss 7 of the bit 3, 70 whereby the coupling sleeve is connected with the bit. The upper portion of the coupling sleeve 2 is provided with interior screw threads 9 and the lower end portion 10 of the safety sleeve or tube is exteriorly 75 threaded to screw into the threaded portion of the coupling sleeve or member 2. The safety sleeve or casing 1, which is of a length to cover the entire string of tools, is designed to be constructed of two or more sections having their contiguous terminals 11 exteriorly threaded for the reception of an 80 interiorly threaded coupling 12, but the safety tube or casing may be constructed in a single piece or any other desired number 85 of sections.

The upper end 13 of the safety sleeve or casing is provided with exterior screw threads 14 and is equipped with an interiorly threaded cap 15. The cap, which consists of 90 a cylindrical body, has the interior threads 16 at its lower portion, and it is provided at its upper end with an outwardly tapered neck or portion 17 having a smooth reduced mouth or opening 18 through which passes 95 the neck 19 of the rope socket 4. The neck 19 is extended to form a guide for the upper end or portion of the safety sleeve or casing, the upper cap 17 constituting the 100 slidable connection between the casing or sleeve 1 and the neck, which is adapted to receive the friction and wear incident to the slidable connection between the safety device and the string of tools. This arrangement relieves the rope or cable 20 of such wear 105 and lessens the liability of breakage. The upper end 21 of the extended neck is arranged exteriorly of the tubular casing or

safety sleeve when the upper drill jar or link is at the limit of its downward movement, and the said upper end 21 is provided with grooves or notches to form a grip 22 to enable the rope socket to be engaged by a suitable fishing tool in event of breakage of the cable.

In case a breakage occurs in any portion of the string of drilling tools, such as the 10 breaking off of the pin of the bit, the breakage of the jars or the stem, or breakage at any point above the boss of the bit where the safety sleeve is connected with the latter, the fact will be indicated to the driller by 15 the load being released from the line when the break occurs. This slackens the rope and reduces the tension thereon. The rope socket will move upwardly in the tubular casing or safety sleeve until it contacts with 20 the reduced or tapered upper portion 17 of the cap 15. The rope socket catches at this point and provides an extra long stroke enabling the string of tools to be jarred up and thereby drawn out of the hole. The 25 safety sleeve or casing affords a complete protection for the string of tools and excludes rock, sand, mud, etc., and affords a freer motion of the jars and prevents their operation from being interfered with by 30 such rock, sand, mud, etc. Also in event of a cave-in before inserting the well casing, the tools, which would otherwise become wedged, will be protected by the casing, the stroke remaining unimpaired. A perfectly 35 straight hole is assured owing to the guiding of the sleeve on the extended neck of the rope socket. As the tools are maintained in a straight line or position by the safety sleeve or casing, there is less liability of a 40 caving-in of the hole.

What is claimed is:—

1. In a drill, the combination with a string of tools including a bit, and a rope socket having a neck, of a safety sleeve or casing extending the entire length of the 45 string of tools and forming a housing for the same and secured at its lower end to the bit, said sleeve or casing having a slide-able connection at its upper end with the neck of the rope socket. 50

2. In a drill, the combination with a string of tools including a bit, and a rope socket having an extended neck, of a safety sleeve or casing receiving the string of tools and extending the entire length of the same 55 and secured at its lower end to the bit, and a cap carried by the upper end of the sleeve or casing and having a reduced portion slide-ably arranged on the extended neck of the rope socket. 60

3. In a drill, the combination with a string of tools including a bit having a threaded boss, and a rope socket provided with a neck, of a safety sleeve or casing re-ceiving the string of tools and extending 65 from the bit to the rope socket, a coupling sleeve carried by the lower end of the safety sleeve or casing and having an interiorly threaded portion to engage the threaded boss of the bit, and means carried by the upper 70 end of the safety sleeve or casing for slide-ably connecting it with the neck of the rope socket. 75

In testimony, that I claim the foregoing as my own, I have hereto affixed my signa-ture in the presence of two witnesses.

CHARLES A. DEMPSEY.
